CLAIM

The ornamental design for a food container as shown and
described.

DESCRIPTION

FIG. 1 is a front view of a first embodiment of the food
container showing our new design.

FIG. 2 is a top view thereof.

FIG. 3 is a rear view thereof.

FIG. 4 is a bottom view thereof.

FIG. 5 is a left view thereof.

FIG. 6 is a top, left perspective view thereof.

FIG. 7 is a right view thereof.

FIG. 8 is a bottom, left perspective view thereof.

FIG. 9 is a front view of another embodiment of the food
container showing our new design.

FIG. 10 is a top view thereof.

FIG. 11 is a rear view thereof.

FIG. 12 is a bottom view thereof.

FIG. 13 is a left view thereof.

FIG. 14 is a top, left perspective view thereof.

FIG. 15 is a right view thereof; and,

FIG. 16 is a bottom, left perspective view thereof.

(Continued)

The broken lines of equal length represent unclaimed subject matter and form no part of the claimed design.
